AUTOMATIC CORRECTING MECHANISM
FOR TIME DEVICES

Charles Schiff, Montclair, N. J.

Application February 9, 1950, Serial No. 143,218

12 Claims. (Cl. 58—35)

1

This invention relates to automatic correcting mechanism for clocks, time recorders, time stamps and other time devices.

It is an object of this invention to provide automatic setting and synchronizing mechanism for clocks, time recorders, time stamps, and other time devices which require correction, which mechanism can be actuated by remote control through an electrically or electronically transmitted impulse or signal, whereby to set a minute hand and/or minute type wheel of such devices to correct time when restarting the devices after a stoppage, and to automatically correct a minute hand and/or minute type wheel of running devices, if either slow or fast, at predetermined intervals, as e. g. every hour, every half hour or every quarter hour.

Illustrative embodiments of this invention are shown in the accompanying drawings, in which:

Fig. 1 is a rear face elevational view of parts of a time device of the time recorder or time stamp type as equipped with one form and arrangement of the automatic correcting mechanism of this invention, said mechanism being shown in its normal initial or inactive position; Fig. 2 is an elevational view of the correcting mechanism per se, showing an operating position thereof when actuated to automatically correct the minute hand and minute type wheel of the running time device, if either slow or fast; Fig. 3 is an elevational view similar to that of Fig. 2, but showing an operating position of the correcting mechanism when actuated to reset the minute hand and minute type wheel of the time device when the latter is started after a stoppage; and Fig. 4 is a fragmentary view similar to that of Fig. 3 but showing a preliminary stage of the re-setting operation.

Fig. 5 is a rear face elevational view of parts of a time device of the time recorder or time stamp type as equipped with another and modified form and arrangement of the automatic correcting mechanism of this invention, said mechanism being shown in its normal initial or inactive position; Fig. 6 is an elevational view of the modified correcting mechanism per se with certain parts omitted, showing an operating position of said mechanism as actuated to reset the minute hand and minute type wheel of the time device when the latter is started after a stoppage; Fig. 7 is a view similar to Fig. 6, but showing a preliminary position of the correcting mechanism preparatory to actuation thereof for automatic correction of the minute hand and minute type wheel of the running time device, if either slow or fast;

2

and Fig. 8 is a similar view showing completion of such correction operation.

Similar characters of reference are employed in the above described views, to indicate corresponding parts.

Referring to the drawings, the reference character 10 indicates the arbor by which is driven the minute type wheel 11 of a time device of the time recorder or time stamp type. The minute hand (not shown) which sweeps the clock dial 12 is driven from the arbor 10 by a suitable gear train, the latter also operating an hour hand and, through suitable agencies, an hour type wheel of the device, all in manner well known to the art. 15 Fixed on the arbor 10 is a ratchet wheel 13 by which operative movement is transmitted to said arbor and the parts driven thereby. Since the ratchet wheel drives the minute hand of the clock dial and the minute type wheel 11 it is 20 provided with sixty teeth. Pivoted on the arbor is a setting lever 14, upon which is pivotally mounted a drive pawl 15 by which the ratchet wheel is actuated. The drive pawl 15 is positively stopped, at the end of a ratchet wheel driving 25 stroke of the setting lever 14, by abutment against a fixed stop piece 16. Also cooperative with the ratchet wheel 13 is a pivoted check pawl 17 which holds the ratchet wheel against retrograde movement and back lash. This check pawl 17 is provided with a cam arm 18 which, under conditions hereinafter explained, is subject to actuation whereby to release or withdraw the check pawl from ratchet wheel engagement, and said check pawl is yieldably urged to ratchet wheel engagement by spring means, such e. g. as the pull 30 spring 19.

A power rotated wheel 20 is provided for normal actuation of the setting lever 14. This power wheel may be driven by any suitable power source, 40 but is preferably driven by a sixty cycle A. C. synchronous motor (not shown), whereby it makes one revolution per minute. Projecting from a face of the power wheel 20 is a trip dog 21 which cooperates with thrust means carried by 45 the setting lever 14. Said thrust means, in a form thereof shown in Figs. 1 to 4 inclusive, comprises a nose-piece 22 which is pivotally mounted on a stud 23 projecting from a face of the setting lever, and so shaped that a free end portion 50 thereof lies in the path of movement of the trip dog 21. Said nose-piece 22 is provided with a tail portion 24 having a stop lug 25 projecting from its lower edge. Also pivoted on said stud 23, for cooperation with the nose-piece 22, is a 55 spring carrier 26 which is disposed to overlie the

tail portion 24 of the nose-piece in normal stopped engagement with the stop lug 25 of the latter. Said carrier 25 is provided with a trigger arm 27 dependent from its free end. A spring which is supported by the stud 23 has one of its arms 28 bearing on an abutment pin 29 with which the carrier 26 is provided; the opposite arm 30 of said spring bears against an abutment lug 31 projecting from the upper edge of the nose-piece tail portion 24.

In normal running operation of the time device, each revolution of the power wheel 20 carries its trip dog 21 into engagement with the nose-piece 22 of the thrust means with which the setting lever 14 is provided, whereby to swing out the latter against the tension of an anchored pull-spring 32 which is coupled thereto. Such out swing of the setting lever carries back the drive pawl 15 relative to the ratchet wheel a sufficient distance to operatively engage a next succeeding tooth of the latter. Thereafter, as the trip dog moves away from and releases the thrust means, the pull-spring 32 retracts the setting lever to normal initial position, thus causing the drive pawl to advance the ratchet wheel, and consequently the clock minute hand and minute type wheel, one minute indicating interval.

In the illustrative embodiment of this invention shown in Figs. 1 to 4 inclusive, one form and arrangement of means is provided which is operative for setting the clock minute hand and minute type wheel to correct time indicating positions when the time device is again started after a stoppage, such e. g. as a stoppage due to an electrical power failure. This arrangement comprises an actuating solenoid 33, the armature 34 of which is projected by a spring means 35 to a normal initial position as determined by a stop pin 36. Connected to the armature 34 is a draw bar 37, the free end portion of which is coupled to the setting lever 14 by a lost motion connection, comprising a coupling pin 38 which projects from the setting lever into a longitudinal slot 39 with which the free end portion of the draw bar is provided. Carried by the draw bar 37 is a thrust pin 40 which is operative, on retraction of the draw bar, to engage the trigger arm 27 of the setting lever thrust means. When the draw bar is in its projected or inactive position (see Fig. 1), the distance between the inner end of the slot 39 and the coupling pin 38 is sufficient to permit free oscillation of the setting lever under normal power wheel actuation; and the distance between the outer end of the slot 39 and the coupling pin 38 is sufficient to permit a degree of lost motion at the beginning of an operative stroke of the draw bar. When the time device is restarted after a stoppage, it will be slow to the amount of elapsed time between the stoppage and restarting thereof. Correction can be made by transmitting to solenoid 33 an energizing impulse, as by momentarily closing a switch at a master clock by which transmission of the impulse through suitable agencies is controlled. When the solenoid 33 is thus momentarily energized, its armature 34 is retracted and released to thereby reciprocate the draw bar 37. Reciprocation of the draw bar causes oscillation of the setting lever 14, whereby to advance the ratchet wheel 13 a time unit interval. These operations are successively repeated to the extent required to bring the clock minute hand and the minute type wheel to correct time indicating positions.

In the above described operation, retractive

movement of the draw bar 37 imparts no operative motion to the setting lever 14 until the outer end of the slot 39 abuts the coupling pin 38, but during such lost motion phase of draw bar movement the thrust pin 40 engages and swings outward the trigger arm 27 of the setting bar thrust means so as to up swing the spring carrier 26 away from the stop lug 25 of the nose piece tail portion 24, thus moving the spring arms 28 and 30 one toward the other so as to put the spring under tension (see Fig. 4). By reason of this, the nose piece 22 is yieldably poised in such manner that it can snap over and away from the trip dog 21 of power wheel 20, as continued movement of the draw bar 37 swings out the setting lever, thereby avoiding obstruction of rotation of said power wheel. After such operation, the thrust means will assume its normal initial position in relation to the setting lever either under gravity or an assisting spring (not shown), when the thrust pin 40 is withdrawn from the trigger arm 27.

In the embodiment of this invention shown in Figs. 1 to 4 inclusive, means is also provided which is operative to synchronize the time device while it is running, whereby to automatically correct the minute hand and minute type wheel, if either slow or fast. The means for this purpose comprises a cam disc 41 which is so related to the ratchet wheel 13 and arbor 10 as to turn therewith. This cam disc 41 is provided with one or more radial notches or recesses 42 indenting its periphery, and so disposed as to be operative once each hour, if one is provided, or every half hour or every quarter hour, if a plurality thereof is provided. Extending from the sides of each notch or recess 42 to the cam disc periphery, in opposite directions, are respective oblique cam sections, comprising a fast correction cam section 43 and a slow correction cam section 44. Pivotedly mounted adjacent to the ratchet wheel 13 and cam disc 41 is a synchronizing lever 45 upon which is carried a roller stud 46 for cooperation with the cam disc 41. This synchronizing lever 45 is provided with a bell-crank arm 47, the free end 48 of which normally abuts the arbor structure 10, thus determining the normal initial or inactive position of the synchronizing lever 45, as yieldably maintained in such position by an anchored pull-spring 49 which is connected with the latter. Said synchronizing lever 45 is actuated by a second solenoid 50, between the armature 51 of which and the free end portion of the synchronizing lever 45 is connected a draw bar 52. The bell-crank arm 47 is provided with a suitably shaped and located cam slot 53 into which extends a lift stud 54 with which the drive pawl 15 is provided. The synchronizing lever 45 is also provided with a suitably located, laterally projecting trip stud 55 which cooperates with the cam arm 13 of the check pawl 17.

In the operation of the synchronizing means, a momentarily energizing impulse is transmitted to the solenoid 50. The transmission of such energizing impulse at suitable time intervals may be controlled by any suitable means cooperative with a master clock, such e. g. as by an auxiliary timer mechanism of the kind disclosed in my co-pending Patent Application Ser. 130,375, filed December 1, 1949. When the solenoid 50 is momentarily energized, its armature 51 is retracted and released to thereby oscillate the synchronizing lever 45. As said synchronizing lever is in swung toward the cam disc 41, its bell-crank

arm 47 is up swung, whereby to carry the cam slot 53 into operative engagement with the lift stud 54 of drive pawl 15, thus disengaging the latter from the ratchet wheel 13. At the same time, the trip stud 55 is carried into operative engagement with the cam arm 18 of the check pawl 17, thereby simultaneously also disengaging the latter from the ratchet wheel 13. The pawls 15 and 17 being thus disengaged from the ratchet wheel 13, the latter is free to be moved either forward or backward as may be required to effect correct setting of the minute hand and minute type wheel of the time device in synchronized relation to the master clock, and thus in correct time indicating positions. If under these circumstances, the time device is running fast, the fast correction cam section 43 of the cam disc 41 will be presented in the path of movement of the roller stud 48 of the in swinging synchronizing lever 45, so that said roller stud will engage and thrust against said fast correction cam section 43, whereby to impart to the freely movable cam disc 41 and ratchet wheel 13 a backward shift which is completed by the entrance of said roller stud into the terminal notch or recess 42 of the cam disc, thereby moving back the ratchet wheel 13 and associated minute hand and minute type wheel of the time device to correct time indicating positions, after which the synchronizing lever returns under pull of spring 49 to normal initial inactive position as the solenoid 50 is de-energized. On the other hand, if the time device is running slow, the slow correction cam section 44 of the cam disc 41 will be presented in the path of movement of the roller stud 46, and will be engaged thereby to shift forward the cam disc 41 and ratchet wheel 13, whereby to shift forward the minute hand and minute type wheel of the time device to correct time indicating positions. It will be obvious that upon return of the synchronizing lever 45 to normal initial or inactive position, the pawls 15 and 17 will be caused to resume normal engagement with the ratchet wheel 13 so that normal running operation of the time device is thereupon resumed.

It may be here pointed out that the scope of correctional shift of the ratchet wheel 13 may be suitably predetermined by the angle and length of the respective fast correction and slow correction cam sections of the cam disc 41, and the number of ratchet wheel teeth included between said cam sections. Ordinarily a shift arrangement to correct up to five minutes fast and five minutes slow would be all that should be required.

Referring now to Figs. 5 to 8 inclusive, a modified and perhaps preferred embodiment of the invention is therein shown, whereby the means operative for both resetting the time device when restarted after a stoppage and for synchronizing the same during running operation thereof are actuated by a single electro-magnetic means or solenoid. In this embodiment, the structures of the power wheel, setting lever, ratchet wheel and cooperative pawls, cam disc and synchronizing lever are substantially the same as above described, and as indicated by corresponding reference characters applied thereto. There is provided, however, a somewhat modified form of the thrust means carried by the setting lever 14, as will be apparent from the following description of said modified embodiment of this invention. The modified structure comprises a single actuating solenoid 56 having a normally

projecting armature 57. Pivotedly mounted adjacent to the solenoid 56 is a bell-crank member 58 to one arm 59 of which the solenoid armature 57 is connected by a link 60. The bell-crank member is yieldably held in solenoid armature projecting position by an anchored pull spring 61 which is connected thereto. Connected with the other arm 62 of said bell-crank member is a draw plate 63. This draw plate 63 is provided at its free end with a dependent arm 64 from the end of which extends a coupler hook portion 65. The draw plate 63 is further provided at its free end with an upwardly extending arm 66 which terminates in a rearwardly projected push finger 67. The synchronizing lever 45 is provided with a coupler stud 68 which projects from a face thereof subject, at proper times, to be engaged by the coupler hook portion 65 of the draw plate 63. In a normal initial position thereof, the lower edge of the draw plate 63 rests and rides upon the arbor structure 10, in which position the coupler hook portion 65 is disposed below and in disengaged relation to the coupler stud 68, whereby the draw plate, if reciprocated in such position, is without operative effect upon the synchronizing lever 45. The body of the draw plate 63 is provided with a suitably located and shaped opening 69 the upper margin 70 of which provides a lift cam section.

Pivoted on the same axis as that of the fulcrum of the synchronizing lever 45 is a unitary frame comprising a forward plate 71 and a rearward plate 72 which are joined together in spaced apart unitary relation by transverse outer and inner tie rods 73 and 74. From the inner end of the rearward plate 72 extends a cam arm 75, the free end of which terminates in an oblique nosing 76. This cam arm 75 extends across and adjacent to the face of the cam disc 41, so that its nosing 76 normally lies in the path of movement of trip stud means 77 which project from said cam disc face. Supported by the frame comprising the plates 71 and 72, so as to be disposed between said plates, is a shift lever 79. Said shift lever 79 is fulcrumed intermediate its ends on the inner transverse tie rod 74 of the frame whereby to provide an inner arm 80 and an outer arm 81. Said arm 81 is provided with a dependent adjustable stop element 82 which is opposed to and normally abuts the outer transverse tie rod 73, whereby to dispose the shift lever in normal operative position relative to the frame, in which position it is yieldably retained by a pull spring 83 which is connected between its outer arm 81 and the downwardly offset ear 78 of the forward frame plate 71. Projecting laterally from the free end portion of the inner arm 80 of the shift lever 79 is a lift pin 84 which extends into the opening 69 of the draw plate 63. Pivoted on the arbor 10 is a shift lever depresser member 85 provided at its free end with a cam nosing 86 which is normally opposed to the path of movement of the coupler stud 68 which is carried by the synchronizing lever 45. This depresser member 85 is provided with a draft arm 87 angular thereto, and the free end of said draft arm terminates in a lateral pull tongue 88 which overhangs the inner arm 80 of the shift lever 79.

When the device is restarted after a stoppage and correction thereof is to be effected by operation of the modified correcting mechanism, such correction can be made by transmitting to the solenoid 56 an energizing impulse, as by

momentarily closing a switch at a master clock by which transmission of the impulse through suitable agencies is controlled. When the solenoid is thus momentarily energized, its armature 57 is retracted and released to thereby actuate the bell-crank member 58. The draw plate 63 being in its lowered normal initial position, actuation of the bell-crank member 58 reciprocates said draw plate, whereby outward movement of the same carries the push finger 67 thereof into engagement with a roller stud 89 with which the setting lever 14 is provided, thus swinging out the latter to position the drive pawl 15 for advancing the ratchet wheel 13 a time unit interval as the setting lever returns to normal position under the pull of spring 32 (see Fig. 6). This operation can be successively repeated to the extent required to bring the clock minute hand and the minute type wheel to correct time indicating positions.

For response to the above described operation, the power wheel engageable thrust means, with which the setting lever 14 is provided, is somewhat modified to comprise a nose piece 90 pivotally mounted on the stud 23 carried by the setting lever, and is provided with a tail portion 91 having a stop lug 92. Also pivoted on the stud 23 is a spring carrier 93 having an abutment lug 94. A spring 95, which is supported on the stud, has one of its arms disposed to bear on the stop lug 92 of nosepiece 90, and its opposite arm to bear on the abutment lug 94. Said spring carrier 93 has a dependent trigger arm 96 which lies in the path of a thrust tongue 97 which projects from the top edge of the draw plate 63. When, during the above described setting operation, the draw plate 63 moves outward, the thrust tongue 97 engages and swings back the trigger arm 96 of the spring carrier 93, thus putting the spring 95 under tension. By reason of this, the nose-piece 90 is yieldably poised in such manner that it can snap over and away from the power wheel trip dog 21, as outward movement of the draw plate is completed, and, therefore, no obstruction to normal rotation of the power wheel 20 is offered.

In the operation of the above described modified form of the correcting mechanism to correct the time device if slow or fast, as the cam disc 41 rotates it carries a trip stud 71 into engagement with the nosing 76 of the cam arm 75, whereby said cam arm is up swung, thus up swinging the frame 71-72 with which it is associated. This effects a like up swinging movement of the shift lever arm 80. Such upward movement of the shift lever arm 80 carries the lift pin 84 into engagement with the lift cam section 70 of the draw plate 63, thus imparting to the latter an uplifting movement which raises its coupling hook 65 in position to engage the coupler stud 68 of the synchronizing lever 45. After this occurs, the solenoid 56 is momentarily energized by an impulse transmitted thereto under the control of a master clock as previously described. When the solenoid 56 is thus energized, it reciprocates the draw plate 63 and oscillates the synchronizing lever 45 so as to actuate the cam disc 41 for slow or fast correction as already above described. As the operative outward stroke of the draw plate 63 occurs, the coupler stud 68 of synchronizing lever 45 is also carried into actuating engagement with the nosing 86 of the depresser member 85, so that the latter is moved to cause its draft arm 87 and pull tongue 88 to pull down 75

the shift lever arm 80, whereby the draw plate 63 may immediately drop down to normal lowered position after completing its synchronizing lever actuating operation, notwithstanding that the cam arm 75 of the frame 71-72 is still engaged and lifted by the trip stud 71, which has not yet passed away therefrom since the effective length of the cam arm must be sufficient to provide e. g. an amplitude of ten minutes, viz. five minutes slow and five minutes fast. The shift lever 79 yields to such downward movement by reason of its yieldable relation to the frame 71-72 which is afforded by the intermediate spring connection 83. Such prompt dropping of the draw plate 63 permits normal running operation of the time device under control of the power wheel 20, but even more important, permits resetting operations of the time device if restarting after a stoppage occurs while the cam arm 75 remains uplifted by a trip stud 71, which otherwise could not be accomplished until said cam arm 75 was released from said trip stud.

It will be obvious that the hereinabove described correcting mechanism for time devices can be controlled by impulses transmitted from a remote point in various ways to the electro-magnetic actuating devices thereof. Optionally, such impulses or signals may be transmitted by a carrier current, differing from normal, over electric light and power lines; by voltage axis shift either above or below an A. C. neutral axis, as disclosed e. g. in U. S. Patents 2,213,384, 2,266,851, or 2,457,607; by radio or other electronic transmission; or in any other manner whereby controlled energization of the electro-magnetic actuating means may be attained.

Having now described my invention, I claim:

1. In a time device having time indicating means, a ratchet wheel for actuating the indicating means, an oscillatable setting lever provided with a drive pawl for driving the ratchet wheel, and power driven means for oscillating the setting lever, in combination with the foregoing elements, electro-magnetic means adapted to be energized by an impulse transmitted thereto from a remote point, a cam disc rotatable with the ratchet wheel, and a pivoted synchronizing lever operable by said electro-magnetic means for cooperation with the cam disc to rotatively shift the same whereby to adjustingly advance or retract the ratchet wheel, said synchronizing lever having means to disengage the drive pawl from the ratchet wheel and thus free the latter for adjusting movement.
2. In a time device having time indicating means, a ratchet wheel for actuating the indicating means, an oscillatable setting lever provided with a drive pawl for driving the ratchet wheel, and power driven means for oscillating the setting lever, in combination with the foregoing elements, electro-magnetic means adapted to be energized by an impulse transmitted thereto from a remote point, means operable by said electro-magnetic means for oscillating the setting lever with ratchet wheel driving effect independently of said power driven means, a cam disc rotatable with the ratchet wheel, and a pivoted synchronizing lever operable by said electro-magnetic means for cooperation with the cam disc to rotatively shift the same whereby to adjustingly advance or retract the ratchet wheel, said synchronizing lever having means to disengage the drive pawl from the ratchet wheel and thus free the latter for adjusting movement.
3. In a time device having time indicating

means, a ratchet wheel for actuating the indicating means, a ratchet wheel for actuating the indicating means, an oscillatable setting lever provided with a drive pawl for driving the ratchet wheel, and a power driven wheel having a trip dog for oscillating the setting lever, in combination with the foregoing elements, electro-magnetic means adapted to be energized by an impulse transmitted thereto from a remote point, a draw member for connection between the armature of the electro-magnetic means and the setting lever and operable by the electro-magnetic means for oscillating the setting lever with ratchet wheel driving effect independently of the power wheel trip dog, a thrust means mounted on the setting lever, said thrust means including a pivoted nose piece engageable by the power wheel trip dog, means operable to tension said nose piece for escape from the trip dog, and said draw member having means for actuating the tensioning means prior to transmission of oscillating movement by the draw member to the setting lever.

4. In combination with the subject matter of claim 3, a cam disc rotatable with the ratchet wheel, a pivoted synchronizing lever for cooperation with the cam disc to rotatively shift the same whereby to adjustingly advance or retract the ratchet wheel, said synchronizing lever having means to disengage the drive pawl from the ratchet wheel and thus free the latter for adjusting movement, a second electro-magnetic means adapted to be energized by an impulse transmitted thereto from a remote point, and means interconnecting the synchronizing lever and the armature of said second electro-magnetic means.

5. In a time device having time indicating means, a ratchet wheel for actuating the indicating means, an oscillatable setting lever provided with a drive pawl for driving the ratchet wheel, and a power driven means for oscillating the setting lever, in combination with the foregoing elements, electro-magnetic means adapted to be energized by an impulse transmitted thereto from a remote point, a cam disc rotatable with the ratchet wheel, said cam disc having at least one recess indenting its periphery from the opposite sides of which extend oblique cam formations, one said formation constituting a fast correction cam and the other formation constituting a slow correction cam, a pivoted synchronizing lever having a roller stud cooperable with the cam disc, said synchronizing lever being adapted to be actuated by the electro-magnetic means whereby to rotatively shift the cam disc for adjustingly advancing or retracting the ratchet wheel, and the synchronizing lever having means to disengage the drive pawl from the ratchet wheel and thus free the latter for adjusting movement.

6. In a time device having time indicating means, a ratchet wheel for actuating the indicating means, an oscillatable setting lever provided with a drive pawl for driving the ratchet wheel, and a power driven means for oscillating the setting lever, in combination with the foregoing elements, electro-magnetic means adapted to be energized by an impulse transmitted thereto from a remote point, means operable by said electro-magnetic means for oscillating said setting lever with ratchet wheel driving effect independently of said power driven means, a cam disc rotatable with the ratchet wheel, said cam disc having at least one recess indenting its pe-

riphery from opposite sides of which extend oblique cam formations, one said formation constituting a fast correction cam and the other formation a slow correction cam, a pivoted synchronizing lever having a roller stud cooperable with the cam disc, said synchronizing lever being adapted to be actuated by the electro-magnetic means whereby to rotatively shift the cam disc for adjustingly advancing or retracting the ratchet wheel, and the synchronizing lever having means to disengage the drive pawl from the ratchet wheel and thus free the latter for adjusting movement.

7. In a time device having time indicating means, a ratchet wheel for actuating the indicating means, an oscillatable setting lever provided with a drive pawl for driving the ratchet wheel, and power driven means for oscillating the setting lever, in combination with the foregoing elements, a cam disc rotatable with the ratchet wheel, a pivoted synchronizing lever cooperative with the cam disc to rotatively shift the same whereby to adjustingly advance or retract the ratchet wheel, said synchronizing lever having means to disengage the drive pawl from the ratchet wheel and thus free the latter for adjusting movement, a single electro-magnetic means adapted to be energized by impulses transmitted thereto from a remote point, a draw member adapted to be actuated by said electro-magnetic means, said draw member being shiftable from a first operative position to a second operative position, said draw member having means effective in its first operative position to engage and oscillate the setting lever with ratchet wheel driving effect independently of said power driven means, said draw member and synchronizing lever having cooperative means effective in the second operative position of the former for detachably connecting the same in operative relation, and means actuated by the rotated cam disc and ratchet wheel for shifting said draw member from its first operative position to its second operative position.

8. A time device as defined in claim 7, wherein the means for shifting the draw member from its first operative position to its second operative position comprises a pivoted shift lever structure having means to engage the draw member, and trip stud means on the cam disc operative to engage and actuate the shift lever structure whereby to shift the draw member from its first operative position to its second operative position.

9. A time device as defined in claim 7, wherein the means for shifting the draw member comprises a pivoted shift lever structure having means to engage the draw member, trip stud means on the cam disc operative to engage and actuate the shift lever structure whereby to shift the draw member from its first operative position to its second operative position, and means actuated by operative movement of the synchronizing lever adapted to release the shift lever structure from shifting engagement with the draw member, whereby the latter will return to its first operative position after operation in its second operative position.

10. A time device as defined in claim 7, wherein the means for shifting the draw member comprises a pivoted frame having a cam arm, trip stud means on the cam disc operative to engage said cam arm, a shift lever pivotally supported by the frame and provided with a shift pin, the draw member having an opening an edge portion of which provides a shift cam section engageable by the shift pin, means to yieldably

hold the shift lever for normal movement with the frame, and means operable by actuated movement of the synchronizing lever adapted to release the shift lever, independently of frame movement, from shifting relation to the draw member, whereby the latter will be immediately returned to its first operative position after operation in its second operative position.

11. In a time device having time indicating means, a ratchet wheel for actuating the indicating means, an oscillatable setting lever provided with a drive pawl for driving the ratchet wheel, and power driven means for oscillating the setting lever, in combination with the foregoing elements, a cam disc rotatable with the ratchet wheel, a pivoted synchronizing lever cooperative with the cam disc to rotatively shift the latter whereby to adjustingly advance or retract the ratchet wheel, said cam disc having at least one recess indenting its periphery from opposite sides of which extend oblique cam formations, one said formation constituting a fast correction cam and the other formation constituting a slow correction cam, said synchronizing lever having a roller stud for cooperation with said cam formations of the cam disc, said synchronizing lever having means to disengage the drive pawl from the ratchet wheel and thus free the latter for adjusting movement, a single electro-magnetic means adapted to be energized by impulses transmitted thereto from a remote point, a draw member adapted to be actuated by said electro-magnetic means, said draw member being shiftable from a first operative position to a second operative position, said draw member having means effective in its first operative position to engage and oscillate the setting lever with ratchet wheel driving effect independently of said power driven means, said draw member and synchronizing lever having cooperative means effective in the second operative position of the former for detachably connecting the same in operative relation, and means actuated by the rotated cam disc and ratchet wheel for shifting the draw member from its first operative position to its second operative position, said latter means comprising a pivoted shift lever structure having means to engage the draw member, and trip stud means on the cam disc operative to engage and actuate the shift lever structure for draw member shifting effect.

12. In a time device having time indicating means, a ratchet wheel for actuating the indicating means, an oscillatable setting lever provided with a drive pawl for driving the ratchet wheel, and power driven means for oscillating the setting lever, in combination with the foregoing elements, a cam disc rotatable with the ratchet

wheel, a pivoted synchronizing lever cooperative with the cam disc to rotatively shift the latter whereby to adjustingly advance or retract the ratchet wheel, said cam disc having at least one recess indenting its periphery from opposite sides of which extend oblique cam formations, one said formation constituting a fast correction cam and the other formation constituting a slow correction cam, said synchronizing lever having a roller stud for cooperation with said cam formations of the cam disc, said synchronizing lever having means to disengage the drive pawl from the ratchet wheel and thus free the latter for adjusting movement, a single electromagnetic means adapted to be energized by impulses transmitted thereto from a remote point, a draw member adapted to be actuated by said electro-magnetic means, said draw member being shiftable from a first operative position to a second operative position, said draw member having means effective in its first operative position to engage and oscillate the setting lever with ratchet wheel driving effect independently of said power driven means, said draw member and synchronizing lever having cooperative means effective in the second operative position of the former for detachably connecting the same in operative relation, and means actuated by the rotated cam disc and ratchet wheel for shifting the draw member from its first operative position to its second operative position, said latter means comprising a pivoted frame having a cam arm, trip stud means on the cam disc operative to engage said cam arm, a shift lever pivotally supported by the frame and provided with a shift pin, the draw member having an opening an edge portion of which provides a shift cam section engageable by the shift pin, means to yieldably hold the shift lever for normal movement with the frame, and means operable by actuated movement of the synchronizing lever adapted to release the shift lever, independently of frame movement, from shifting relation to the draw member, whereby the latter will be immediately returned to its first operative position after operation in its second operative position.
